AMINOALKYL ESTERS OF α,α -DIARYL- γ,δ UNSATURATED ALIPHATIC ACIDS AND THE PRODUCTION THEREOF

Carl Peter Krimmel, Evanston, Ill., assignor to G. D. Searle & Co., Chicago, Ill., a corporation of Illinois

No Drawing. Application December 10, 1949,
Serial No. 132,401

18 Claims. (Cl. 260—469)

This invention relates to aminoalkyl esters of α,α -diaryl- γ,δ -unsaturated aliphatic acids, to salts thereof and to methods of producing such compounds. In particular this invention relates to basic esters having the general structural formula

wherein R and R' are lower alkyl radicals or hydrogen, Ar and Ar' are monocyclic aromatic carbocyclic radicals, Alk is a lower alkylene radical, and X and X' are lower alkyl radicals.

The compounds of this invention are useful as medicinal agents. Certain of them are active as spasmolytic agents, while others are useful as local anesthetics and as adrenolytic and autonomic blocking agents. The compounds of this invention are also useful as intermediates in the formation of more complex basic esters for therapeutic and pharmacological purposes.

In the foregoing structural formula R and R' represent hydrogen or the same or different lower alkyl radicals such as methyl, ethyl, propyl, and isopropyl radicals. Ar and Ar' include aromatic carbocyclic radicals such as phenyl, tolyl, xylenyl, and related homologues, and chlorophenyl, bromophenyl, iodophenyl, methoxyphenyl, ethoxyphenyl, hydroxyphenyl and related monocarbocyclic aromatic radicals. The alkylene radical, Alk, is a bivalent radical containing 2 to 8 carbon atoms derived from a saturated aliphatic hydrocarbon and includes ethylene, propylene, trimethylene, tetramethylene, hexamethylene, octamethylene, 2,3-butylene, 1,3-butylene, 1,2-butylene, and similar bivalent aliphatic hydrocarbon radicals. X and X' represent the same or different lower alkyl radicals and comprise alkyl radicals containing 1 to 8 carbon atoms such as methyl, ethyl, propyl, isopropyl, butyl, isobutyl, amyl and octyl radicals.

The basic esters of this invention are usually viscous oils which are insoluble in water but soluble in common organic solvents such as ether, halogenated hydrocarbons, hydrocarbons, lower alcohols, ketones, and esters. The compounds are useful both in the form of the free bases or as acid addition or quaternary ammonium salts. The bases form stable salts with a variety of inorganic and strong organic acids. These salts are generally soluble in water, and therefore constitute a preferred form of the invention. Among the acids which are suitable for forming acid addition salts are hydrochloric, hydrobromic, hydroiodic, sulfuric, sulfamic, phosphoric, citric, 55 vention involves the heating of the organic acid

tartaric, malic, maleic, succinic, benzene-sulfonic, toluene-sulfonic, lactic, oxalic, acetic, propionic, gluconic, benzoic, cinnamic, and related acids.

The organic bases also form quaternary ammonium salts when treated with an alkyl, alkenyl, hydroxyalkyl or aralkyl ester of a halogen acid, sulfuric acid or an aromatic sulfonic acid. Among such esters are methyl chloride, methyl iodide, ethyl bromide, ethyl chloride, allyl chloride, allyl bromide, crotyl chloride, methallyl bromide, ethylene chlorohydrin, ethylene bromohydrin, n-propyl chloride, benzyl chloride, benzyl bromide, methyl benzenesulfonate, ethyl toluenesulfonate, naphthylmethyl chloride, dimethyl sulfate, diethyl sulfate, and related esters. The quaternary ammonium salts of the basic esters of this invention are generally crystalline, stable solids which are readily soluble in water and aqueous solutions. The quaternary ammonium salts generally exhibit physiological activities which are different from those of the tertiary bases. For example, many of the quaternary ammonium salts are adrenergic agents, whereas the tertiary bases are not.

25 Compounds of this invention may be made by a variety of methods. The organic acid of the formula

30 may be converted to the corresponding acid halide or acid anhydride by treatment with thionyl chloride, phosphorus oxychloride, phosphorus trichloride, phosphorus tribromide, acetic anhydride, or similar reagents, and the resulting acid derivative may be condensed with a dialkylamino-alkanol of the formula

wherein Alk, X and X' have the meanings given hereinabove. The basic ester is formed directly and may be isolated by conventional methods of organic chemistry. The esters may also be produced by reacting an alkali metal salt of the organic acid of the foregoing formula with an aminoalkyl halide of the formula

50 wherein Z represents a halogen of atomic number greater than 9, preferably a middle halogen such as chlorine or bromine. An alternative method of production of the esters of this invention involves the heating of the organic acid

3

of the foregoing type with an aminoalkyl halide of the formula given hereinabove, in a solvent such as acetone, isopropanol, ethanol, methyl ethyl ketone and related water-miscible organic liquids. During this reaction the elements of hydrogen halide are split out with the formation of a basic ester as its hydrohalide salt. The organic bases are isolated from the reaction mixture by neutralization and extraction and are generally purified by distillation under reduced pressure. In certain instances the salts of the basic esters, which form during the reaction mixture, are crystalline substances which precipitate from the reaction mixture and may be separated and purified as such.

The following examples illustrate in more detail my invention without limiting it in spirit or in scope. It will be obvious to those skilled in the art that numerous modifications relating to temperature, proportions, solvents, and other reaction conditions may be made without departure from the invention. Similarly, related amino alcohols or acids may be used without deviating from the scope of the invention. The relative amounts of materials are given in parts by weight.

Example 1

320 parts of β -methallyldiphenylacetic acid, 163 parts of β -diethylaminoethyl chloride and 4000 parts of anhydrous isopropanol are refluxed and agitated for five hours. The solvent is stripped off under vacuum at steam temperature and the residue of β -diethylaminoethyl β -methallyldiphenylacetate hydrochloride is taken up in water. The water solution is extracted with ether to remove insoluble materials. The aqueous solution is made alkaline, and the organic base is extracted with ether. The ether solution is treated with anhydrous potassium carbonate, filtered and evaporated. The residue of β -diethylaminoethyl β -methallyldiphenylacetate is distilled at 205-210° C. at 2 mm. pressure. 10 parts of the basic ester in 560 parts of anhydrous ether are treated with an equivalent of anhydrous hydrogen chloride in isopropanol with good agitation. The precipitate of the hydrochloride is removed by filtration, washed with ether and dried. After recrystallization from methyl ethyl ketone, β -diethylaminoethyl β -methallyldiphenylacetate hydrochloride forms colorless crystals melting at 153.5-155° C. The basic ester has the formula

Example 2

120 parts of β -diethylaminoethyl β -methallyldiphenylacetate and 76 parts of ethyl bromide in 160 parts of methyl ethyl ketone are heated in a closed vessel at 100° C. for four hours. Upon chilling colorless plate-like crystals separate, which are collected on a filter, washed with methyl ethyl ketone and dried. The quaternary ammonium salt, β -triethylaminoethyl β -methallyldiphenylacetate bromide, melts at 173-175° C.

Example 3

β -Diethylaminoethyl allyldiphenylacetate is prepared by the method of Example 1 using 345 parts of allyldiphenylacetic acid, 189 parts of β -diethylaminoethyl chloride, and 4000 parts of isopropanol. It distills at 197-205° C. at 1.5 mm.

70 75

4

pressure. It forms a hydrochloride which melts at 114-115.5° C. It has the formula

Example 4

80 parts of β -diethylaminoethyl allyldiphenylacetate and 50 parts of ethyl bromide are reacted at 100° C. for four hours in 120 parts of methyl ethyl ketone. The crystalline quaternary ammonium salt is removed by filtration, washed with methyl ethyl ketone and dried. β -triethylaminoethyl allyldiphenylacetate bromide forms colorless crystals which melt at 146-150° C.

Example 5

β -Diethylaminopropyl allyldiphenylacetate is prepared as in Example 1 from 300 parts of allyldiphenylacetic acid, 180 parts of β -diethylaminopropyl chloride and 4000 parts of anhydrous isopropanol. It is a colorless oil which distills at 187-198° C. at 0.5 mm. pressure. It forms a crystalline hydrochloride which melts at 120-125° C. after recrystallization from a mixture of methyl ethyl ketone and ether. It has the formula

Example 6

β -Dibutylaminoethyl allyldiphenylacetate is produced from 134 parts of β -dibutylaminoethyl chloride, 175 parts of allyldiphenylacetic acid and 250 parts of dry isopropanol, according to the method of Example 1. It is a viscous, nearly colorless oil which distills in the range of 207-212° C. at 1 mm. pressure. It has the formula

Example 7

β -Dimethylaminoethyl crotyldiphenylacetate is made by the method of Example 1 from 160 parts of crotyldiphenylacetic acid, 65 parts of β -dimethylaminoethyl chloride and 200 parts of dry isopropanol. It is a fluid colorless oil which distills at 192-196° C. at 0.9 mm. pressure. It has the formula

Example 8

γ -Diethylaminopropyl allyldiphenylacetate is made as above from 200 parts of allyldiphenylacetic acid, 120 parts of γ -diethylaminopropyl chloride and 270 parts of anhydrous isopropanol. It distills at 197-200° C. at 1 mm. pressure. It has the formula

252 parts of allyldiphenylacetic acid are converted to the acid chloride by reaction with 410 parts of thionyl chloride in 2400 parts of carbon tetrachloride, as in Example 6. After removal under vacuum of the excess thionyl chlo-

ride and the solvent, the residue of allyldiphenyl-acetyl chloride is taken up in 350 parts of anhydrous ether. To this solution are added with efficient agitation 145 parts of δ -diethylaminobutanol. The precipitate of δ -diethylaminobutyl allyldiphenylacetate hydrochloride is separated and dissolved in warm water. The aqueous solution is chilled, washed with ether, then made alkaline and extracted with ether. The ether extract is washed with water and dried and evaporated. The residue of δ -diethylaminobutyl allyldiphenylacetate is distilled at about 196-202° C. at 0.5 mm. pressure. It is a viscous light-colored oil. It has the formula

I claim:

1. A member of the group consisting of (a) basic esters of the formula

wherein R and R' are members of the group consisting of hydrogen and lower alkyl radicals, Ar and Ar' are monocyclic aromatic carbocyclic radicals, Alk is a lower alkylene radical and X and X' are lower alkyl radicals, and (b) acid addition salts and (c) quaternary ammonium salts thereof.

2. A salt of a basic ester of the formula

wherein R and R' are lower alkyl radicals, Ar and Ar' are monocyclic aromatic hydrocarbon radicals, Alk is a lower alkylene radical and X and X' are lower alkyl radicals.

3. A salt of a basic ester of the formula

wherein R is a lower alkyl radical, Ar and Ar' are monocyclic aromatic hydrocarbon radicals, Alk is a lower alkylene radical and X and X' are lower alkyl radicals.

4. A salt of a basic ester of the formula

wherein Ar and Ar' are monocyclic aromatic hydrocarbon radicals, Alk is a lower alkylene radical and X and X' are lower alkyl radicals.

5. A salt of a basic ester of the formula

wherein Ar and Ar' are monocyclic aromatic hydrocarbon radicals, Alk is a lower alkylene radical and X and X' are lower alkyl radicals.

6. A salt of a basic ester of the formula

wherein Alk is a lower alkylene radical and X and X' are lower alkyl radicals.

7. A salt of a basic ester of the formula

wherein Alk is a lower alkylene radical and X and X' are lower alkyl radicals.

8. A salt of a basic ester of the formula

wherein X and X' are lower alkyl radicals.

9. A salt of a basic ester of the formula

wherein X and X' are lower alkyl radicals.

10. A salt of a basic ester of the formula

wherein X and X' are lower alkyl radicals.

11. A salt of β -diethylaminoethyl allyldiphenylacetate.

12. A salt of β -diethylaminoethyl β -methallyldiphenylacetate.

13. A salt of β -diethylaminopropyl allyldiphenylacetate.

14. β -Diethylaminoethyl allyldiphenylacetate hydrochloride.

15. β -Triethylaminoethyl allyldiphenylacetate bromide.

16. β -Diethylaminoethyl β -methallyldiphenylacetate hydrochloride.

17. β -Triethylaminoethyl β -methallyldiphenylacetate bromide.

18. β -Diethylaminopropyl allyldiphenylacetate hydrochloride.
